UNITED STATES PATENT OFFICE

138,607

DESIGN FOR A HAT OR SIMILAR ARTICLE

Jacob Schoer, Brooklyn, N. Y.

Application December 28, 1943, Serial No. 112,107

Term of patent 3½ years

(Cl. D3—13)

To all whom it may concern:

Be it known that I, Jacob Schoer, a citizen of the United States, residing at Brooklyn, in the county of Kings and State of New York, have invented a new, original, and ornamental Design for a Hat or Similar Article, of which the following is a specification, reference being had to the accompanying drawing, forming part thereof.

The dominant feature of my invention resides in the combination of a calot hat of the type disclosed having dependent scarf like elements attached to the opposing rear side portions of the calot, as shown.

I claim:

The ornamental design for a hat or similar article, substantially as shown and described.

JACOB SCHOER.
